BOWTIE RACK

Charles Miller, 2413 Grove Ave.,
Berwyn, Ill. 60402

Filed May 20, 1968, Ser. No. 12,011

Term of patent 14 years

Int. Cl. D6—01

U.S. Cl. D33—8

FIG. 1

FIG. 2

FIG. 3

FIG. 1 is a perspective view of the bowtie rack, illustrating my new design;

FIG. 2 is a side view of the same bowtie rack; and

FIG. 3 is a bottom view of the same bowtie rack.

The bowtie shown in dotted lines in FIGURE 1 are for illustrative purposes only.

I claim:

The ornamental design for a bowtie rack, as shown and described.
